BARBER CHAIR

Nathan Cooper and Russell V. Raulie, Chillicothe, Mo.

Application September 18, 1956, Serial No. 42,993

Term of patent 14 years

(Cl. D15—3)

Fig. 1.

Fig. 2.

Fig. 3.

Fig. 1 is a perspective view of a Barber chair, showing our new design;

Fig. 2 is a rear elevational view; and

Fig. 3 is a side elevational view thereof.

The characteristic features of our design are shown by means of full lines in the drawing.

We claim:

The ornamental design for a Barber chair, as shown and described.
